UNITED STATES PATENT OFFICE

IVAR T. WEDIN, OF FLINT, MICHIGAN, ASSIGNOR TO A C SPARK PLUG COMPANY, OF FLINT, MICHIGAN, A COMPANY OF MICHIGAN

SPEEDOMETER TEMPERATURE COMPENSATOR

Application filed February 6, 1929. Serial No. 337,929.

This invention relates to measuring instruments and has been designed more particularly as an improvement in the temperature compensating provision for magnetic speedometers such as are used on motor vehicles.

An object of the invention is to provide a compensator having maximum efficiency in rendering the reading of the instrument accurate within a wide range of temperature changes.

Another object is to accomplish the above mentioned object with a structural arrangement which is simple, inexpensive and easily applied.

Other objects and advantages will be apparent from the following description.

In the drawings:

Figure 1 is a vertical section through a magnetic speedometer, my improved temperature compensator being incorporated therein.

Figure 2 is a transverse section substantially on line 2—2 of Figure 1.

Figure 3 is a top plan view of a modification, parts broken away and in section to illustrate the use of the compensating device.

Figure 4 is a vertical section substantially on line 4—4 of Figure 3.

Figure 5 is a section corresponding to Figure 1, this figure showing a modified form of the compensator.

Figure 6 is a view taken from line 6—6 of Figure 5.

Figure 7 is a perspective of the compensator used in the form of the invention shown by Figure 5.

Figure 8 is a section on line 8—8 of Figure 6.

Figure 9 is a plan view of a modified form corresponding to the form shown by Figure 3.

Figure 10 is a section on line 10—10 of Figure 9.

Figure 11 is a plan view of the compensator used in Figure 9, and

Figure 12 is a section on line 12—12 of Figure 11.

Referring by reference characters to the drawing and first to Figures 1 and 2, a frame

5 is housed within a casing 7. The frame is to carry the speedometer parts and the casing is seated against a flange 9 of the frame to which it may be secured in any conventional way, not shown. The frame has a 55 stem part 11 externally threaded as at 13 for attachment to a nut associated with the coupling means for the flexible drive shaft. The frame is also internally bored to receive a worm shaft 15, the latter angularly related to 60 the front face of the instrument. At its outer end worm shaft 15 is formed with openings to receive the usual connecting means associated with the flexible drive shaft. These features are not a part of this invention and 65 not fully illustrated.

The worm shaft 15 is geared to a second worm shaft 17, this being the so-called second worm shaft of the speedometer. At one end shaft 17 has an eccentric 19 serving to reciprocate a pawl 21, controlled by spring 23, the pawl operating through a suitable means to rotate the figure wheels of an odometer, one of the odometer wheels being designated by 25.

The frame at its top portion has diverging arms, one of which is shown at 27. To these arms are connected lugs extending from a conical field plate 29.

The end of shaft 15 is reduced, the reduced 80 end passing through an opening in a bar magnet 31, the ends of which are upturned to lie in parallel relation with the adjoining wall of the conical field plate. The extreme end of shaft 15 is riveted over to hold the magnet 85 in position, as will be obvious.

A similarly shaped conical speed cup or indicating member 33 is located between the field plate and the magnet, its conical wall being parallel with the conical wall of the field plate. This speed cup is mounted on a spindle 35 journalled in bearings carried by jewel cups 37 and 39 positioned in alignment and located one in the end of shaft 15 and the other in the apex of the conical field plate. A hair spring 41 is secured to the spindle 35 at one end and to a regulator 43 rotatably mounted about the upper bearing cup. An end of regulator 43 is bent over 100

the extreme end of spindle 35 to limit the axial movement of the same.

Means such as struck up flanges 45 and 47 on the field plate and speed cup limit the rotation of the latter under the influence of the hair spring. The field plate is open at its front to render visible the indicating characters on the speed cup and is provided with a pointer 49 to aid in reading the instrument.

A cover plate 51, a glass 53 and a bezel 55 are used at the front of the instrument, these parts being conventional and not constituting a part of this invention.

The construction described is very efficient for the reason that due to the upturned ends of the magnet and the inclosed parallel walls of the speed cup and the field plate shaped to inclose the speed cup and magnet and shielding all the available magnetic flux for efficient influence on the speed cup, substantially all the magnetic energy is utilized. This is particularly true in the case of the conical walled speed cup and field plate with the magnet ends positioned in parallelism with said walls.

As is well known, the electrical resistance of the non-magnetic speed cup increases as the temperature rises with the result that the readings of the instrument tend to be too low at temperatures above that at which the instrument is calibrated and too high at lower temperatures. One known way of correcting for this error is to provide a shunt including a part, preferably an alloy, the magnetic permeability of which decreases as the temperature rises.

In connection with an instrument as described I use a thermo-compensating unit 57 formed of a thermo-compensating alloy which is shaped like the magnet and attached thereto by pinching the metal to distort it in places to form clamping ears 59.

A compensator of this kind is found to be highly efficient. In previous expedients employing an alloy compensator, the compensator has been used as or as a part of an external shunt which is to be distinguished from the active magnetic field, the field active upon the speed cup. In the present case the equivalent of the shunt is within the magnet itself.

As is well known, at temperatures lower than those for which the instrument is calibrated, the speed cup electrical resistance is relatively lower and there is a tendency for the eddy currents therein to increase. At this time the magnetic permeability of the compensator is high. Therefore fewer lines of force pass through the active field, more being shunted through the compensator than at the calibration temperature.

On the other hand when the temperature rises above that for which the instrument is calibrated and owing to the greater elec-

trical resistance of the speed cup at the higher temperature as a result of which readings would tend to be too low, the lesser magnetic permeability of the compensator causes less of the magnetic flux to be shunted from the pole through the compensator and more to pass through the speed cup. There is therefore a compensation provided for in which the lines of force are at all times under control, the proportion passing through the shunt so controlling the proportion through the active field as to insure correct readings at all temperatures.

We have therefore a temperature compensator unit which is attached to and made a part of the rotating magnet, rotating axially thereof and positioned within the magnetic field and functioning therewithin. It controls within the magnetic field the intensity of magnetic current before passing through the speed cup walls and previous to its influence upon the speed cup. It gives maximum accuracy of speed indication at all temperatures within a reasonable range.

Since also the full strength of the magnet is being used within the speed cup a more definite control is had than with other arrangements, both the active field and the shunt being shielded. It is possible to quite accurately determine the electrical resisting characteristics of the speed cup metal under temperature changes and to so determine the dimensions of the compensator as to secure very accurate reading at all temperatures.

Figures 3 and 4 show another type of instrument in which the invention may be embodied. In this second form there is a fixed U-shaped magnet 70 within which is a rotor 71. The magnet is held in position by a clamp 73. Rotor 71 is driven by shaft 75. Speed cup 77 is carried by a spindle 79 which is suitably journaled so that the cup rotates between the poles in such a way that by far the greater part of the lines of force are cut by the rotor as it rotates. At 79' is a compensator unit. This unit has the same characteristics as compensator 57 of the form described above.

In this second embodiment of the invention the compensator is within the rotor, and having magnetic permeability characteristics the opposite of the electrical resistance of the speed cup aids in maintaining in the active field across the gap such a flux as to produce accurate readings at all temperatures. While the strength of the field is not decreased or increased before acting upon the speed cup as in the form described above, the intensity of the magnetic current effective through the cup is directly controlled and made uniform.

In this second form of the invention the intensity of the magnetic current generated by the rotor is directly controlled by the compensator which will increase or decrease the

strength of the magnetic current passing through the speed cup according to its permeability to proportionately compensate for the relatively high or low resistance of the speed cup during temperature changes.

Figure 5 shows a form of the invention similar to that of Figure 1 but with a somewhat different form of compensator. In this figure the reference characters are the same as for the corresponding parts in Figure 1. The compensator comprises a stamping shown in perspective in Figure 7 and designated by reference character 101. It has slotted wings 103 diverging from the apertured base 105. Projections 107 are to be bent over the magnet and serve to hold the compensator in position. The leg portions of the slotted wings 103 are in contact with the magnet poles. This form of compensator is easily made and as easily assembled. It will adjust itself automatically to form positive contact points with the poles irrespective of any warpage which may occur. Owing to its shape as compared with the shape of the compensator shown in Figure 1 it tends to shorten its shunt action across from pole to pole. The action is substantially the same as the compensator shown in Figure 1 but is believed, for the reasons stated, to be a preferable form.

Figures 9-12 show a modified form of the compensator used in the relation shown by Figure 3. In this form the magnet is not illustrated. The rotor 71 carries a compensator differing in shape from that shown in Figure 3. This form of compensator comprises an apertured base 109 from the opposite ends of which are diametrically arranged axial arms 111. At the top the arms are extended in both directions circumferentially as at 113. As shown in Figure 10, the compensator is held by the same fastening means which is used to secure the rotor to its shaft. The operation is substantially the same as in the form of invention shown by Figure 3. The greater electrical resistance of the speed cup tending to cause the readings to be too low at high temperature is compensated by the lesser permeability of the compensator causing an increase in the effective magnetic field.

I claim:

1. In combination, a bar magnet having a base portion and ends extending angularly from said base portion, said ends of said magnet being curved in transverse cross-section, and a thermo-sensitive compensator within said magnet, said compensator being secured to said base portion of said magnet and having slotted wings contacting with the corners at said ends of said magnet.

2. In combination, a bar magnet having a base portion and ends bent back toward each other and at an acute angle to said base portion, and a thermo-sensitive compensator

within said magnet, said compensator being secured to said base portion of said magnet and having slotted wings contacting with the corners at said ends of said magnet.

In testimony whereof I affix my signature. 70
